METHOD OF AND MEANS FOR CUTTING
WELL CASINGS OR PIPESGeorge E. Justice, Houston, Tex., assignor to
Houston Oil Field Material Company, Inc.,
Houston, Tex., a corporation of Delaware

Application May 12, 1941, Serial No. 393,941

24 Claims. (Cl. 164—0.8)

This invention relates to new and useful improvements in method of and means for cutting well casings or pipes.

This application is a continuation-in-part of my pending application filed November 12, 1940, Serial No. 365,158.

One object of the invention is to provide improved means for cutting pipe from the well bore when a cut is desired to be made.

An important object of the invention is to provide improved means for cutting a pipe without necessitating the removal of the running pipe from the well bore when it is necessary to change the cutting knives.

Another object of the invention is to provide an improved cutting device which is adapted to be connected in the usual string of pipe and which includes means for cutting the pipe, said means being arranged so as to be insertable within, and removable from, said pipe by a wire line.

Still another object of the invention is to provide an improved device, of the character described, wherein its bore is arranged to receive a pipe-cutting tool, said bore having means disposed therein for orienting the pipe-cutting tool, whereby the proper operation of the same is assured and a more rugged device is provided.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, of a cutting device constructed in accordance with the invention.

Figure 2 is a view, similar to Figure 1, wherein the device is in cutting position.

Figure 3 is a view in elevation of the orienting sleeve,

Figure 4 is a horizontal cross-sectional view taken on the line 4—4 of Figure 1,

Figure 5 is a horizontal cross-sectional view taken on the line 5—5 of Figure 1,

Figure 6 is a horizontal cross-sectional view taken on the line 6—6 of Figure 1,

Figure 7 is a horizontal cross-sectional view taken on the line 7—7 of Figure 1,

Figure 8 is a horizontal cross-sectional view taken on the line 8—8 of Figure 1, and

Figure 9 is a horizontal cross-sectional view taken on the line 9—9 of Figure 2.

In the drawings, the numeral 10 designates an inside pipe-cutting device which is connected into a string of pipe or tubing (not shown). The cutting device 10 is provided with an elongate, hollow, cylindrical body or housing 11 which has an internally screw-threaded box 12 at its upper end and has its lower end 13 convex so that its upper end may be connected to a string of tubing or pipe and run into the well. The body 11 is provided with a central bore 14 which extends throughout the length of said body and communicates with the bore of the tubing (not shown). The bore 14, below the box 12, is provided with screw threads 15, and below said screw threads the bore is enlarged so as to form an enlarged bore 16.

A plurality of radial ports 17 communicate between the exterior of the body 11 and the interior of the enlarged bore 16, and are preferably placed at the lower end of said enlarged portion. A plurality of radial slots 18 are provided in the body 11 in the same plane as the ports 17 (Figures 1 and 6). The exterior of the body 11, below the slots 18, is cut downwardly so as to form a recess 19, so that the slots 18 may be more easily formed. The recess 19, after the slots 18 have been formed, receives plugs 20 which have downwardly and outwardly curved tops 21. The plugs 20 may be welded or otherwise secured in the body, thus forming the outer portion of the slots 18. A sleeve 22, having external screw threads at its upper end, is screwed into the bore 14 and into the threads 15. The lower end of the sleeve 22 depends downwardly into the chamber 16, and is provided above its lower end with a plurality of ports 23.

The body 11 is provided, at a point below the ports 17 and the slots 18, with a radial port 24 which is enlarged and cut so as to be circular in cross-section at its outer end and reduced at its inner end so that a triangular-shaped pin 25 may be inserted therein. It is pointed out that the pin 25 is provided with an enlarged, circular head 26 which abuts the shoulder formed by the reduced inner end of said port. The pin 25 extends inwardly a short distance into the bore 14 of the housing, and is held in the body 11 by a nut 27 having external screw threads which screw into the threads 28 provided in the outer end of the port 24 (Figures 1 and 7).

A cutting device A may be lowered into the body 11 by a wire line, or by any other suitable means. The device A is provided with an elongate circular mandrel 29 which is provided with external screw threads 30 at its lower end and

a reduced, upstanding, screw-threaded pin 31 at its upper end. The mandrel 29, below the pin 31, is cut so as to be triangular in cross-section at 32, see Fig. 4. This triangular portion 32 of the mandrel 29 extends downwardly a short distance, and is provided with a downwardly and outwardly sloping shoulder 33 where the triangular portion is terminated. The outer portion of the shoulder 33 extends outwardly to the full distance of the rest of the mandrel 29 (Figure 5). Surrounding the mandrel, at a point opposite the ports 17 and the slots 18, is a sleeve 34 which has its upper end 35 underlying the outwardly sloping shoulder 33 and tapered correspondingly to said shoulder so that a continuous outwardly sloping surface is had. The upper portion of the sleeve 34 that does not underlie the sloping shoulder 33 extends upwardly past the tapered surface 35 of said sleeve.

A plurality of cutter deflecting plates 37 are secured to the sloping top 35 at points in register with the triangular faces of the triangular-shaped portion 32 of the mandrel 29. The plates 37 may be held on the shoulder 33 by screws 38 or other suitable means. The outer surface of the sleeve 34 is reduced at a point below the tapered surface 35, and is provided with a plurality of outwardly directed pins 39 at its lower end. Below the sleeve 34 a portion of the mandrel 29 is surrounded by a tubular sleeve 40 which fits snugly and slidably engages over the mandrel 29. The sleeve 40 is provided with a plurality of elongated slots 41, and the mandrel 29 is provided with a plurality of outwardly directed pins 42 which are movable within said slots. It is pointed out that the pins 42 may be screwed into the mandrel 29 or otherwise affixed thereto. Thus, the mandrel 29 and the sleeve 40 are locked together so that they may not rotate in relation to each other.

The sleeve 40 has a sliding fit within the bore 14 of the body 11, and extends downwardly to substantially the end of the mandrel. The lower end of the mandrel is externally screw-threaded, and carries an internally screw-threaded nut 43 which abuts the lower end of the sleeve 40; thus securely fastening said sleeve upon the mandrel. The upper end of the sleeve 40 is provided with a circular, countersunk, elongate recess 44, the upper end of which surrounds the sleeve 34, and is provided with a pair of opposed openings 45 which receive the pins 39 of the sleeve 34. Thus, the sleeve 34 and the sleeve 40 are connected and a limited telescopic movement between the two is allowed.

Underlying the sleeve 34 and the bottom of the recess 44, and confined therebetween, is a coiled spring 45'. The spring 45' will urge the sleeve 34 to the position shown in Figure 1 at all times, unless downward pressure is exerted upon the sleeve 34. Thus, it can be seen that the spring 45' may be compressed as shown in Figure 2 so as to allow movement of the sleeve 34 downwardly, but when the pressure is released from the sleeve 34, said spring will move it to its original position as shown in Figure 1.

The outer portion of the lower end of the sleeve 40 is cut at an angle, thus forming a helical portion 46 at the bottom thereof. An elongate slot 47 extends vertically from the highest point of said helical opening up the side walls of said sleeve. Obviously, as the mandrel and the sleeve 40 are lowered into the bore 14, the lower edges of the sleeve will engage the pin 25. Thereupon, the pin 25 will ride up the edges of the helical

opening 46 and cause the mandrel and the sleeve to rotate until the pin and the slot 47 are in vertical alinement. Then, the sleeve and the mandrel may pass downwardly until the pin 25 engages the upper end of the slot 47. Since the sleeve and the mandrel are rigidly secured together, this alining action will cause the mandrel to come to rest in the same position each time it is lowered into the bore 14.

A head 48 is provided on the upper end of the mandrel 29, and has its lower end countersunk with a recess 49 which has its uppermost end 50 reduced and internally screw-threaded so as to receive the pin 31 of the mandrel 29. Thus, the mandrel 29 and the head 48 are connected. A plurality of milling means or cutters, or knives 51 are pivotally carried by the head 48, and are mounted in a plurality of upwardly extending slots 52 provided in the lower end of said head. The knives or cutters 51 are so positioned as to lie against the faces of the triangular portion 32 of the mandrel 29, so that their outer edges, when in the position shown in Figure 1, may not extend outwardly farther than the circumference of the head 48. It is pointed out that a portion of the head 48 will slide between the knives 51 and extend downwardly past the pivot point of said knives which are in alinement with the portion 36 of the sleeve 34. It is also to be noted that the knives 51 are in alinement with the deflecting plates 37.

The upper end of the head 48 is reduced and carries circular packing 53 which extends outwardly a slight distance from the circumference of said head. The uppermost end of the head 48 is provided with an internally screw-threaded opening 54 to which is suitably attached a fishing neck 55. This fishing neck is provided with a plurality of downwardly directed ports 56 which communicate with the interior of the head 48. Above the pin 31 of the mandrel 29 there is provided a plurality of outwardly directed ports 57 so that fluid may flow through the ports 56, through the head 48, out through the ports 57, and down through the enlarged bore 16, and either out through the opening 17 or the slots 18. With this construction it is possible to wash as the cut is being made, due to the fact that as soon as the ports 57 move to a point below the lower end of the sleeve 22 the fluid may wash the knives and the cuttings.

The sleeve 40 is provided with an elongate slot 58 which lies beneath the slot 47. As will be noted in the drawings, the slot 58 is considerably shorter than the slot 47. Lying within the slot 58 is a rocker arm 59 which is pivoted near its central portion on a pin 60. The lowermost end of the arm 59 is provided with an inwardly extending lug 61. The slot 58 is provided with a port 62 which communicates with the interior of the sleeve 40.

The mandrel 29 is provided with a recess 63 which is the same shape as the lug 61, only somewhat larger, so that the lug 61 may move in and out of said recess. When the mandrel is within the sleeve 40, in the position shown in Figure 1, the pin 25 will depress the rocker arm 59 against the tension of a spring 64, and move it out of said recess. It is pointed out that as the tool is run into the well, the spring 64 will urge the uppermost end of the rocker arm 59 outwardly and keep the lug 61 engaged within the recess 63.

In operation, the body or housing 11 is connected to the tubing or other running means to be used and inserted into a well casing 65.

When the position has been reached at which it is desired to cut, the pipe-cutting device is lowered into the well, preferably by a wire line. The orienting shoe 46, due to its helical shape, will strike the pin 25 and align said pin with the slot 47. As the pin 25 rides up within the slot 47, it will strike the rocker arm 59 which has been previously urged into its locking position by the spring 64. The pin 25 will push the upper end of said arm inwardly, thereby removing the lug 61 from the recess 63 and unlocking the mandrel and the sleeve 40. At this time the head 48 is within the sleeve 22 and the knives 51 are in the position shown in Figure 1. It is pointed out that shear pins 66 may be employed to hold said knives in such a position.

It is also pointed out that by means of the orienting device herein mentioned, the knives 51 will at all times be in position so that they may be moved outwardly through the slots 18. This is accomplished by applying pump pressure down through the tubing into the housing 11. This pump pressure will flow downwardly through the bore of the tubing and will enter the housing, striking the upper end of the head 48, and by means of the packing 53, will act upon said head to move the same downwardly. It is pointed out that a portion of the fluid is free to flow down through the ports 56, through the head and out through the ports 57 so as to allow circulation of the fluid around the cutting knives before they reach their fully extended position as shown in Figure 2.

As the pump pressure is applied, the tubing is rotated and the housing, being connected to the tubing, will also be rotated and carry the knives around therewith. As is obvious, as the pump pressure is increased, the head 48 will be moved farther downwardly, thus moving the knives 51 farther outwardly through the slots 18. The portion of the head 48 lying between the knives 51 will strike the upper portion 36 of the sleeve 34, thereby moving the sleeve downwardly against the tension of the spring 45'. The pin 42, riding within the slots 41 of the sleeve 40, will keep the sleeve and the mandrel in alignment as well as the pins 39 of the sleeve 34 riding within the slots 45 of the upper portion of the sleeve 40. Thus, all of the parts are locked in alignment and the mandrel is free to move downwardly as the pin 25 has moved the rocker arm 59 into position so as to free or unlock the mandrel and the sleeve 40, and the pipe is continued to be rotated and the pump pressure increased so as to completely cut the casing 65.

As the head 48 is pumped downwardly, the packing 53 will pass the ports 23, thus allowing all the fluid to flow through said ports, and thereby indicate to the operator that the cut is completed.

Oftentimes the knives 51 will break or become dull, and in such instances it is desirable to replace said knives. To accomplish this removal of the knives, the pump pressure acting upon the head 48 is shut off and a suitable fishing tool or overshot is lowered and attached to the fishing neck 55. When said fishing tool or overshot engages the fishing neck 55, the neck may then be pulled upwardly, thereby moving the head 48 upwardly whereby the knives 51 will be withdrawn from the slots 18. Thus, the entire assembly A is withdrawn from the bore 11 and up through the tubing. When the head 48 is pulled upwardly, the mandrel 29 will slide upwardly into the position at which it was originally run into

the well; thus allowing the rocker arm 59 to again engage within the recess 63 and lock the sleeve 40 and the mandrel 29 together. In this manner the knives may be readily changed and the device again lowered into the well. During this procedure the knives will again enter the slots 18 and will continue to cut on the same plane or at the same place on which they were originally cutting. This is due to the fact that the position between the casing 65 and the body 11 has not been changed, because the body does not have to be moved in order to remove the knives.

It is pointed out that while the knives are within the slots 18, said slots act to reinforce said knives and prevent their moving in relation to the body 11. As can be seen in all cutting operations, where it is necessary to use several sets of knives, the plane of cutting after each change of knives must be the same and it is necessary to locate the point at which the cut was stopped. Furthermore, by means of the orienting device, as stated hereinbefore, there is no possibility of the knives not entering the slots 18 when proper pump pressure is applied. Also, the possibility of a portion of the structure being left in the well is substantially eliminated. With this type of tool, the pipe desired to be cut may be severed; however, in many instances, it is desirable to cut what is commonly called a "window" or a complete section of the pipe. As can be seen, all of these cutting operations may be easily performed with this type of structure.

Thus, a structure is had in which the knives may be quickly and easily changed a number of times and reinserted into the well a number of times without the necessity of orienting the original position each time between the body 11 and casing 65, and resulting in a much faster cutting or removing of a section of said casing.

Various changes, alterations and modifications may be made in the size, shape and arrangement of the herein described elements, within the scope of the appended claims.

What I claim and desire to secure by Letters Patent is:

1. A pipe-cutting device for lowering into a pipe in a well bore including, a housing having a plurality of openings therein, cutting means movable within the housing and through the openings, means for orienting the cutting means within the housing, means for guiding the cutting means through said openings and into engagement with the wall of the pipe whereby a cut may be made, and means for interlocking the cutting means and the housing whereby said cutting means and said housing may be rotated so that a cut may be made.

2. A pipe-cutting device which is adapted to be lowered into a well bore including, a housing having a plurality of openings, cutting means movable within the housing and through the openings, means for orienting the cutting means within the housing whereby the cutting means may be removed and reinserted any number of times without changing the original position between the housing and the pipe, and means for interlocking the cutting means and the housing whereby said cutting means and said housing may be rotated so that a cut may be made.

3. A pipe-cutting device which is adapted to be lowered into a well bore including, a housing having a plurality of openings therein, cutting means movable within the housing and through the openings, means for orienting the cutting

means within the housing, means for moving said cutting means into cutting position after the same has been oriented, and means for interlocking the cutting means and the housing whereby said cutting means and said housing may be rotated so that a cut may be made.

4. A pipe-cutting device which is adapted to be lowered into a well bore including, a housing having a plurality of openings therein, cutting means movable within the housing and through the openings, means for orienting the cutting means within the housing, means for moving said cutting means into cutting position after the same have been oriented, and means for interlocking the cutting means and the housing whereby said cutting means and said housing may be rotated so that a cut may be made.

5. A pipe-cutting device which is adapted to be lowered into a well bore including, a housing having a plurality of openings therein, cutting means movable within the housing and through the openings, means for orienting the cutting means within the housing, means for moving said cutting means into cutting position after the same have been oriented, and means for washing while the cut is being made.

6. A pipe-cutting device for lowering into a pipe in a well bore including, a housing having an opening therein, cutting means movable within the housing and through the opening, means for orienting the cutting means within the housing, means for deflecting the cutting means through said opening and into engagement with the wall of the pipe whereby a section of the pipe may be cut, and means for interlocking the cutting means and the housing whereby said cutting means and said housing may be rotated so that a cut may be made.

7. A pipe-cutting device for lowering in a well bore including, a housing having a plurality of openings therein, cutting means slidable within said housing, means connected to said cutting means and within said housing for orienting the cutting means within said housing, and means for effecting movement of said cutting means through said openings after said housing is predeterminedly positioned within the well bore.

8. A pipe-cutting device for lowering in a well bore including, a housing having a plurality of openings therein, a tubular fluid-pressure receiving conductor connected to the upper end of said housing whereby said housing is suspended therefrom, cutting means movable within and through the conductor and housing and out through the openings, and pressure responsive means for actuating said cutting means and forcing said cutters out through the openings.

9. A pipe-cutting device for lowering in a well bore including, a housing having a plurality of openings therein, a tubular conductor connected to the upper end of said housing whereby said housing is suspended therefrom, cutting means movable within and through the conductor and housing and out through the openings, means on the upper end of said cutting means responsive to fluid pressure so as to move said cutting means into cutting position, and means for orienting the cutting means and the housing when said cutting means is moved into said housing.

10. A pipe-cutting device for lowering in a well bore including, a housing having a plurality of openings therein, a tubular conductor connected to the upper end of said housing whereby said housing is suspended therefrom, cutting means movable within and through the conductor

5 tor and housing and out through the openings, means on the upper end of said cutting means responsive to fluid pressure so as to move said cutting means into cutting position, means for orienting the cutting means and the housing when said cutting means is run into said housing, and means for washing before the cut is made and during the cutting operation.

11. A pipe-cutting device including, a housing having a plurality of openings therein and an axial opening extending therethrough, means for running the housing into the pipe desired to be cut, a mandrel movable within the housing, cutters pivotally mounted on said mandrel, means for orienting the mandrel within the housing, and means for moving the mandrel downwardly and thereby the cutters outwardly so that a cut may be made.

12. A pipe-cutting device including, a housing having a plurality of openings therein and an axial bore extending therethrough, a mandrel movable within the housing, a head on one end of said mandrel, a sleeve slidably confined on the opposite end of said mandrel, cutters pivotally carried by said mandrel, and means for moving said sleeve and thereby the cutters into cutting position so that a cut may be made when the housing is rotated.

13. A pipe-cutting device including a housing having an opening, a cutter carrier movable into and out of the housing, a cutter movably carried by the carrier, means to project the cutter through said opening of the housing, means in the housing coacting with the carrier to orient the latter thereby to cause the cutter to register with the opening upon replacement of the cutter carrier into the housing following removal of the cutter carrier from the housing, and spring means carried by the cutter carrier for moving said cutter back into the housing, preparatory to removal of the cutter carrier from the housing.

14. A pipe cutting device adapted to be lowered into a well bore, including a housing having an opening, cutter carrying means movable into and out of the housing, means to effect movement of the cutter through said opening and thereby out of the housing, and means for orienting the cutter carrying means whereby following removal and upon replacement in the housing to dispose the cutter in registry with the opening of the housing.

15. A pipe cutting device in accordance with claim 14, wherein there are means for moving the cutter back into the housing subsequent to movement thereof out of the housing, thereby to enable the cutter carrying means to be bodily removed from the housing.

16. A pipe cutting device in accordance with claim 14, wherein there are spring means for moving the cutter back into the housing subsequent to movement thereof out of the housing, thereby to enable the cutter carrying means to be bodily removed from the housing.

17. A pipe cutting device in accordance with claim 14, wherein the opening of the housing has a wall formed to engage the cutter upon movement of the cutter out of the housing thereby to cause the housing to move the cutter in a circle to effect the cut upon rotation of the housing.

18. In a pipe cutting device adapted to be lowered into a well bore, a housing, a unit movable into and out of the housing and including milling means and carrying means for said mill-

ing means, means to mount said milling means on the carrying means for movement in one position thereof to lie exteriorly of the housing so as to cut the pipe, and in a second position to lie inwardly of the exterior of the housing whereby to enable the unit to be moved into and out of the housing, means to actuate the milling means to occupy said two positions, means to orient the unit upon reinsertion of the unit in the housing thereby to cause the milling means to be disposed in its original position with relation to the housing, subsequent to removal of the unit to replace or sharpen the milling means, and means for effecting rotation of the milling means by and upon rotation of the housing.

19. A pipe cutting device in accordance with claim 18, wherein the means to actuate the milling means to lie inwardly of the exterior of the housing includes a spring actuated device which upon removal of the unit from the housing effects movement of the milling means to said second position in which latter position the milling means lies inwardly of the exterior of the housing.

20. A pipe cutting device in accordance with claim 18, wherein the means for effecting rotation of the milling means by and upon rotation of the housing includes means to interlock the housing and milling means together.

21. In a pipe cutting device adapted to be lowered into a well casing a rotatable guide member movable into and out of the casing to and from a predetermined position therein, a cutting member movable into and out of the casing adapted to engage said guide member so as to be guided thereby into engagement with the casing, and means to cause rotation of the guide member and thereby the cutting member to effect cutting of the casing.

22. In a pipe cutting device in accordance with claim 21, wherein there is means to connect the members together to operate in unison.

23. A method of cutting well casings or the like wherein the cutting means is removable from the casing and is replaceable therein to occupy the same position with relation to the casing upon replacement, which resides in removably disposing a cutting means within a housing and lowering the cutting means and its housing to the point of cut, then in projecting the cutting means to lie exteriorly of the house to effect the cut, then in withdrawing means from the housing while the latter remains fixed to enable the cutting means to be replaced or sharpened, and then in reintroducing the cutting means into the housing and re-projecting same from the housing so that the cutting means will continue its cut at the same point of inception of the cut.

24. A method of cutting well casings or the like wherein the cutting means is removable from the casing and is replaceable therein to occupy the same position with relation to the casing upon replacement, which resides in lowering a combined cutting means and guiding means therefor into the casing to a predetermined point of cut so as to position the cutter with respect to said point of cut, then in withdrawing the cutting means from the casing while the guiding means remains stationary within the latter at the point of cut, thereby to permit sharpening or replacing of the cutting means, and then reintroducing the cutting means into the well and in engagement with the guiding means so that the cutting means will be guided and thereby positioned to continue its cut at the point of inception of the cut.

GEORGE E. JUSTICE.
